DESIGN.

—o—
W. L. JACOBS.

CARPET.

No. 17,252.

Patented Apr. 12, 1887.

UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 17,252, dated April 12, 1887.

Application filed February 18, 1887. Serial No. 228,128. Term of patent 32 years.

To all whom it may concern:

Be it known that I, WINTHROP L. JACOBS, a citizen of the United States, residing in East Orange, in the State of New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

The design consists of four separate figures, A, B, C, and D, and occupying the spaces between these larger figures a ground, E.

The figure A is found at the upper and lower parts of the photograph. The figure B is found above A and to the left. The figure C is found above A and to the right, and also in part at the upper left corner of the photograph. The figure D is found above the center of the photograph and toward the right. These figures are of irregular flat shapes and have varying lichen-like outlines, with projecting moss or lichen-like sprays, and are ornamented in the same way, all as is clearly shown in the photograph. A is the largest of these figures or connected groups, and C is the small-

est. B has the general shape of a three-pointed star with recurved points. The mass of all four of these figures is built up solidly in the same general way, as shown. The ground 35 E consists of disconnected groups nearly filling the larger spaces between the main figures of the design, and generally consisting of an open rose figure, (less prominent than the main figures of the design,) and connected smaller 40 leaf- and -blossom sprays, and conventional figures filling the interspaces, such as those appearing at the center of the right edge and at the left lower corner of the photograph, and the three small star-shaped flowers at the left 45 upper corner. This ground E includes all of the parts shown in the photograph that are not connected with any of the four main figures of the design, and is inconspicuous in comparison with such main figures.

What I claim as new, and desire to secure by Letters Patent, is—

1. The design for carpets, consisting of the figure A, substantially as shown and described.
2. The design for carpets, consisting of the 55 figures A B C D and the ground E, substantially as shown and described.

WINTHROP L. JACOBS.
